ELECTRICALLY DRIVEN VEHICLE

Application filed May 29, 1930, Serial No. 457,304, and in Great Britain July 19, 1929.

This invention relates to electrically driven vehicles, equipped with dynamo-electric machines which are capable of regeneration, and has for its object to provide means whereby, 5 in the event of the driver removing his foot from the power pedal, the circuits will automatically close and remain closed during the whole time the machine continues to act as a generator and will automatically open when 10 the machine, by reason of its reduced speed, ceases to generate at a higher voltage than that of the line. Alternatively, means may be provided whereby the circuits can automatically be broken immediately the hand 15 brake, foot brake or reverse lever is employed so that it will be impossible for the driver to apply power and braking at the same time, or to put the vehicle in reverse whilst the circuits are closed.

20 In the accompanying drawings,

Figure 1 illustrates, diagrammatically, one method of arresting the controller drum in the regenerative position.

25 Figure 2 illustrates another method by which the controller drum can be electrically arrested in the regenerative position.

Figure 3 shows an alternative form of magnetic pawl.

30 Figure 4 illustrates diagrammatically another method of pedal control.

Referring to the drawings, 1 is the armature of a compound wound dynamo-electric machine, the series and shunt field windings 2, 3 of which have variable resistances 4 and 35 5 which are connected in series therewith respectively and are controlled by a starting and speed changing resistance controller 22 operated by a power pedal A. The circuit is completed through contactors 16-16^x 40 which are respectively connected with stationary contacts 20-20^x in well known manner.

In the arrangement shown in Figure 1 the controller drum 22 is arrested at the position 45 of maximum regeneration, when the driver takes his foot off the power pedal, by means of a magnetically operated pawl 26 which may take the form of a polarized armature pivoted at 26° and is adapted to engage be- 50 hind the shoulder 25^a of a cam or segmental

catch plate 25 fixed to the shaft of the controller drum. The pole pieces of the magnet 28 are energized by means of a winding 28^a in series with the main circuit, the current through which is reversible, whilst the winding 26^a of the polarized armature 26 is connected in series with the shunt field winding 3, the current through which is unidirectional.

The arrangement is such that, when the 60 machine is acting as a motor and the current is flowing in one direction through the magnet winding 28^a, the pivoted pawl 26 is held in its inoperative position by the attraction of the pole 28' of the magnet 28, but when the machine commences to act as a generator and the direction of flow of current through the magnet winding 28^a is reversed, the pivoted pawl is attracted by the pole 28° into the position shown in Figure 1 in which it engages the shoulder 25^a on the cam 25 to hold the controller drum in the position of maximum regeneration. When the speed of the vehicle drops below that required to sustain regeneration the current through the magnet winding 28^a is insufficient to hold the pawl 26 in its operative position and the controller drum, being thereby released, is returned to the zero position by the action of the spring of B the power pedal. The shoulder 25^a on the cam is preferably inclined away from the radial in order to facilitate the release of the pawl.

70 Figure 2 shows another arrangement for retaining the controller drum 22 in the middle or regenerative position when the driver takes his foot off the power pedal. In this case the winding 28^a of the electro-magnet 28, 75 is of high resistance and connected across the supply poles 6 and 7 by means of a polarized relay which is excited by two windings 29 and 29^a. The heavy winding 29 is connected in series with the main circuit in which the direction of current varies accordingly as the dynamo-electric machine is acting as a generator or as a motor. The fine winding 29^a, 80 as shown, is connected in series with the shunt field winding 3 of the dynamo-electric machine and therefore carries a current which is unidirectional. The winding 29^a may, al- 85 90 95 100

ternatively, be a high resistance coil in circuit between trolley poles 6 and 7, this circuit being preferably broken by the action of the governing control drum 22, as shown 5 in Fig. 3, so that the high resistance coil is not excited when current is cut off from the dynamo-electric machine.

A reverse current relay having an armature 30 carrying a switch 30^b is adapted to 10 move to cause switch 30^b to complete the circuit from circuit 18 through the contacts 30^a to one side of the winding 28^a of the electro-magnet 28. When in consequence of the power pedal being released, the dynamo-electric machine commences to act as a generator, 15 the armature 30 with its switch 30^b will move so as to close its circuit and the resulting excitation of the winding 28^a of the electro-magnet will cause the pawl 26 to be attracted 20 into engagement with the cam 25 so as to arrest the return movement of the controller drum at the position of maximum regeneration. When regeneration ceases, the armature 30 moves in the opposite direction, there- 25 by opening the circuit and allowing the pivoted pawl 26 to be released from engagement with the cam 25 by means of a spring 26^b, whereupon the controller drum is free to return to the back or "off" position under the 30 influence of the power pedal spring B.

Figure 3 shows an alternative method of arresting the controller drum 22 in the middle or regenerative position. In this case the vertical rod 31 which connects the power pedal with the controller drum is provided 35 with a collar 31^a which is adapted to be engaged by a trip lever 33^a pivoted on the armature 33 of an electro magnet 34. The winding 35 of this magnet is connected and excited in the same way as shown in Figure 2. When the controller drum 22 is being pushed 40 forward for driving purposes and the rod 31 is moved upwardly by the forward action of the power pedal, the trip lever 33^a will lift 45 and allow the collar 31^a to pass. When, however, the dynamo-electric machine is regenerating and the electro magnet 34 is consequently excited, the trip lever 33^a will prevent 50 the rod 31 and hence the controller drum 22 returning beyond the point at which regeneration is at its maximum. When regeneration ceases the electro magnet 34 will lose its 55 excitation and the armature 33 and trip lever 33^a, being thereby released, will be free to take up a position, such as that indicated in dotted lines, so that the collar can pass and the controller drum return to the neutral or "off" position.

The operation of the magnetically operated pawl 26 of Fig. 2 or trip lever 33^a of Fig. 3, in releasing the controller drum, instead of being controlled by the effect of electrical regeneration, may be made to depend upon the driver moving a control, such 65 as, for instance the foot brake, in which case

the magnet circuit may include a switch 35^a adapted to be opened on the operation of said foot brake.

In all the above arrangements the power pedal may be so connected that it moves with 70 the drum in both directions and is consequently held in an intermediate position when the controller drum is retained in the regenerative position by the aforesaid pawl or trip lever.

The necessity for the use of a magnetically operated device for the purpose of arresting the controller drum 22 in the regenerative position can, however, be dispensed with 80 and the pawl or its equivalent arranged to be mechanically released by the operation of a movable part, such as, for instance, a hand brake lever.

An arrangement for this purpose is shown in Figure 4. A catch piece 40 having a hook 40^a and a short arm 40^b and being pivotally mounted at one side of the cam 44 is adapted to engage behind shoulder 41 of the quadrant 42 on a lever or arm A which is connected with the controller drum 22 and urged 90 toward raised position by spring B. The cam 44 is pivotally mounted at 45 and connected by a link 46 with brake lever 47 so that as the latter is moved the cam 44 will be turned about the pivot 45. Turning movement of the cam 44 in one direction causes it to engage and raise the short arm 40^b, so depressing the long arm and hook 40^a against the pull of spring 40^a, thus releasing the quadrant 42. Of course rotary 100 movement of the cam 44 in the reverse direction displaces it away from the arm 40^b so that the spring 40^a may move the long arm with its spring 41 upward as the quadrant 42 is moved to the point where its shoulder 41 lies to the rear of the hook 40^a and may hold the hook 40^a in raised engaging position until the cam 44 is rotated in the reverse direction. The power pedal 24 is mounted on the same axis as the lever 43 110 aforesaid, which is connected with the control drum, and rotates the latter in the forward direction by means of a shoulder 22^a, between which and a corresponding shoulder 43^a on the boss of said lever there is a clearance of about 15°. The operation of this mechanism is as follows:—Normally, the catch piece 40 lies below the quadrant-faced projection 42 on the lever 43 operating the control drum. When the driver depresses 120 the power pedal, the lever 43 is rotated to turn the control drum, the quadrant-faced projection 42 on said lever riding over the catch piece 40 until the regenerative position is passed, when the catch piece, by means of a spring 40^a, snaps into position behind the quadrant-faced projection. If now the driver takes his foot off the power pedal, the lever 43, and consequently the controller 130 drum, is arrested at the regenerative posi-

125
130

tion by the catch piece 40, in which position it will remain until the driver operates either the hand brake, foot brake or reverse lever, in either of which cases the said catch piece 5 will be moved against its spring 40^a out of engagement behind the quadrant-faced projection, whereupon the control drum will return to the "off" position.

10 In each of the above described arrangements the circuits of the dynamo-electric machine, when the driver takes his foot off the power pedal, are kept closed by arresting the return movement of the controller drum at the position of maximum regeneration, in 15 which both the series and shunt resistances are short-circuited.

We claim:

1. In a system for an electrically driven vehicle, a dynamo-electric machine, controlling means therefor including a controller device having a neutral position and a plurality of operating positions, means operable for actuating said device to one of said operating positions, means for returning said device to 20 the neutral position after an operation of said first-named means and means responsive to the change of direction of the current flow for retaining said device in one of said operating positions.

2. In a system for an electrically driven vehicle, a source of electrical energy, a dynamo-electric machine for driving said vehicle, controlling means for associating said machine with said source including a controller having a neutral position and a plurality of operating positions, means operable for actuating said controller to said operating positions, and means effective only while power is being delivered by said machine to said 30 source for preventing said controller from being returned to the neutral position, after an operation of said second-named means.

3. In a system for an electrically driven vehicle, a source of electrical energy, a dynamo-electric machine for driving said vehicle, controlling means for associating said machine with said source including a controller having a neutral position and a plurality of operating positions, means operable for actuating said controller to any of said operating positions, and means effective after an operation of said second-named means for actuating said controller to the position providing the maximum return of energy by said machine to said source and for maintaining said controller in said last-named position while energy is being returned by said machine to the source, said last-named means 45 returning the controller to the neutral position after said machine ceases to deliver energy to said source.

4. In a system for an electrically driven vehicle, a source of electrical energy, a dynamo-electric machine for driving said vehicle, controlling means for associating said ma-

chine with said source including a controller having a neutral position and a plurality of operating positions, means operable in either of two directions along a predetermined path for actuating said controller to said positions, and means for preventing the operation of said second-named means in only one of said directions, said last-named means being effective only while said machine returns power to the source.

5. In a system for an electrically driven vehicle, a source of electrical energy, a dynamo-electric machine for driving said vehicle, said machine having an armature, controlling means for associating said machine with said source including a controller movable into a plurality of operating positions, a stop member associated with said controller and movable therewith, magnetic means movable into or out of engagement with said member for restricting movement thereof, and means for energizing said second-named means in accordance with the direction of flow of current in the armature of said machine, whereby a current flow in one direction causes said second-named means to engage the member for defining a predetermined limit of movement for said controller, and current flow in the opposite direction causes the second-named means to withdraw from engagement with said member.

6. In a system for an electrically-driven vehicle, a source of electrical energy, a dynamo electric machine for driving said vehicle, controlling means for associating said machine with said source including a controller movable along a predetermined path into a plurality of operating positions, a stop member associated with said controller and movable therewith, and magnetic means cooperating with said member comprising a magnetic structure, an armature body pivotally related to said structure, an element pivotally affixed to said body and adapted to engage said member, said element pivoting with reference to the body for permitting the member to pass in only one direction of travel, said body pivoting with reference to the structure for permitting the member to pass the element in the opposite direction of travel, and means for energizing the structure in accordance with the direction of flow of current in the armature of said machine, for preventing said body from pivoting with reference to the structure when the current flows in a predetermined direction said energization permitting the body to pivot when the current flows in the opposite direction.

7. In a system for an electrically-driven vehicle, a source of electrical energy, a dynamo-electric machine for driving said vehicle, controlling means for associating the machine with the source including a controller movable to a neutral position and a plurality of operating positions, means operable for

actuating said controller to one of said operating positions, biasing means for returning said controller to the neutral position after an operation of said second-named means, a stop member affixed to said controller and movable therewith, and a magnetic device associated with said member comprising a magnetic structure, an armature element for said structure movable into or out of engagement with said member, an electrical winding for said structure, an electrical winding for said element, one of said windings being energized from an electrical source of energy of constant polarity, the other winding being adapted to carry a current varying in direction of flow with the current in the armature of said machine, whereby when the current in the armature of said machine flows in a predetermined direction in excess of a predetermined magnitude, the element is moved into engagement with the member for preventing return of the controller to the neutral position after an operation of said second-named means, and when the armature current flows in the opposite direction, said element is withdrawn from engagement with said member.
